CLAIM

The ornamental design for an engine cover, as shown and described.

DESCRIPTION

FIG. 1 is a perspective view of an engine cover embodying the invention;

FIG. 2 is a front view of the engine cover of FIG. 1;

FIG. 3 is a first side view of the engine cover of FIG. 1;

FIG. 4 is a second side view opposite the first side view of the engine cover of FIG. 1;

FIG. 5 is a top view of the engine cover of FIG. 1;

FIG. 6 is a bottom view of the engine cover of FIG. 1; and,

FIG. 7 is rear perspective view of FIG. 1.
